[57] CLAIM

The ornamental design for a door latch assembly, as shown and described.

DESCRIPTION

FIG. 1 is a top, front, and left side perspective view of a door latch assembly showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view of the door frame-mounted portion of the assembly;

FIG. 7 is a left side elevational view of the door-mounted portion of the assembly;

FIG. 8 is a right side elevational view of the door frame-mounted portion of the assembly;

FIG. 9 is a right side elevational view of the door-mounted portion of the assembly; and,

FIG. 10 is a top, front, and left side perspective view thereof, showing the handle portion rotated to an alternate position, and the bolt portion retracted.
